[57] CLAIM

The ornamental design for a throwing ax, as shown and described.

DESCRIPTION

FIG. 1 is a front elevational view of the throwing ax of my design, the rear elevational view being herein omitted because it is a mirror image of the front elevational view;

FIG. 2 is a left side elevational view of my throwing ax, as shown in FIG. 1;

FIG. 3 is a right side elevational view of my throwing ax, as shown in FIG. 1;

FIG. 4 is a top plan view of my throwing ax, as shown in FIG. 1;

FIG. 5 is a bottom plan view of my throwing ax, as shown in FIG. 1;

FIG. 6 is a cross-sectional view of my throwing ax taken along line 6—6 of FIG. 1;

FIG. 7 is a cross-sectional view of my throwing ax taken along line 7—7 of FIG. 1; and

FIG. 8 is a cross-sectional view of my throwing ax taken along line 8—8 of FIG. 1.
